UNITED STATES PATENT OFFICE

148,535

DESIGN FOR A COMBINATION BOTTLE OPENER AND MUDDLER

Frank E. Hamilton, Jr., Milwaukee, Wis.

Application March 25, 1946, Serial No. 127,924

Term of patent 14 years

(Cl. D44—29)

To all whom it may concern:

Be it known that I, Frank E. Hamilton, Jr., a citizen of the United States, residing at Milwaukee, in the county of Milwaukee and State of Wisconsin, have invented a new, original, and ornamental Design for a Combination Bottle Opener and Muddler, of which the following is a specification, reference being had to the accompanying drawing, forming a part thereof, and in which:

Figure 1 is a top plan view; Fig. 2 a side elevation; Fig. 3 a front end view; Fig. 4 a rear end view; and Fig. 5 a side elevation partly in section on line 5—5 of Fig. 1 of a combination bottle opener and muddler embodying my new design.

The characteristic features of my design reside

in the head and the aperture therein as shown particularly in Fig. 1 of the drawings.

I claim:

The ornamental design for a combination bottle opener and muddler, substantially as shown and described.

FRANK E. HAMILTON, JR.
